ADJUSTABLE AND REVERSIBLE SPORT
IDENTIFICATION

Porter C. Wilson, 320 E. Elvira Road, and Norman C. Adams, 4258 Camino de la Celina, both of Tucson, Ariz.

Filed Mar. 22, 1962, Ser. No. 181,603
2 Claims. (Cl. 2—1)

This invention relates to an adjustable and reversible identification for participants in an athletic sport and, in particular, one which permits of the maximum freedom of movement.

A main object of the invention is to provide a colorful, fully adjustable and reversible identification means that will replace or complement game uniforms.

A further objective is to minimize the number of suitings normally required by teams in athletic contests by the mere reversal or substitution of player and/or team designation.

An additional objective is to provide the apparel and identifications of a flexible but durable plastic material which may readily be cleaned.

Still another object is to provide an adjustable sport apparel with reversible team or player identifications which do not restrict the body movement of the player and wherein all excess belting is frictionally secured and will not flap about during play.

A still further object is to provide a player number means of identification which may be separately used without a belt or wherein the emblem unit may be individually used or with the uniform apparel.

With these and other objects in view the invention may consist in the details of construction and combination of parts, as will be more fully understood from the following description and specifications, when read in conjunction with the accompanying drawings.

By way of further explanation, heretofore the problems involved in suiting out a group or team for the playing of numerous games, were fitting the individual sizes with proper color, number and emblem identification. When changes were made in team personnel, refitting became necessary. The original purchase of such apparel is always expensive with the cleaning and maintenance of such equipment over a period of time even more expensive. This equipment can be used only for the team for which it was intended and very little interchangeable use between the teams was possible. Accordingly, the problem of placing a team emblem without interfering with number identification has also been a problem.

The subject invention provides complete size adjustment quickly and simply with complete interchangeability between teams or individuals made possible. The invention provides decorative color contrast or complement for two teams by quickly turning the attire inside out. The same is true of providing a different team emblem upon the reverse side of the emblem circle.

This invention also provides emblem silhouettes to be placed upon a contrasting color background, and interchanging the emblems by reversing the circle. Provision is also made for the method of placing a team emblem upon a player without interfering with number identification and also enables the same to be displayed when used with any uniform.

It will be appreciated, in addition, that through the use

2

of the flexible durable plastic material it may easily be washed, eliminating the usual cleaning and maintenance problems. Further, the invention provides individual and team identification which does not restrict body movement and any excess belting is frictionally secured and does not flap about during play.

The invention provides top number identification which may be used separately without the belt and there is also provided a bottom belt and emblem which may be used separately with any uniform or alone. It has been contemplated to provide a system whereby the identification circles are self centering upon the chest and back of the usual sized individual.

It is also an object to provide a sliding retainer for the apparel belting allowing a simple piece of belting to be adjustable to all sizes while retaining the loose or surplus belt end.

In the drawings:

FIGURE 1 is a front view of the uniform apparel with the body of the wearer shown in dotted lines.

FIGURE 2 is a partial rear view of the same.

FIGURE 3 is a sectional view taken on the lines 3—3 of FIGURE 1.

FIGURE 4 is a sectional view taken on the lines 4—4 of FIGURE 1.

FIGURE 5 is a plan view of one of the two stays that are to be mounted on the lower end of a shoulder strap.

FIGURE 6 is a top plan view of a slide retainer showing the opposed serrated grooves whereby the main belt portion may be securely engaged and adjusted.

FIGURE 7 is a side elevation of the same.

FIGURE 8 is a cross-sectional view taken on the line 8—8 of FIGURE 7 and shows the belt portions secured thereto, while

FIGURE 9 is a sectional view of the slide retainer taken on the line 9—9 of FIGURE 8 showing the relative positions of the belting that is secured in the retainer.

In the drawings where like reference numerals denote like parts, the numeral 10 refers to the body of the wearer, shown in dotted lines throughout the drawings. The number designations 12 and 14 are shown on the front and rear of the apparel 16 and are secured by rivets or staples 18 to the crossed shoulder straps 20 and 22. It is to be observed that these number designations are formed of doubled plastic material and although these two plastic sections are secured by staples 18 they are separable to enable the insertion of the two shoulder straps 20 and 22 in crossed relationship. It is to be noted that the dotted lines 10 reflecting the wearer's body do not conform to the actual size or shape of a human. The number "77" shown on the apparel is indicated at 24 has only been shown in FIGURE 1 and may be secured by rivets, staples or other means to the members 12 and 14.

The crossed shoulder straps 20 and 22 have plastic stays 26 located on the lower portions in the front to accommodate looseness due to an excess of the belt material. Connecting plates 28, also of plastic, are located on the two front sides to secure the folded ends 30 and 32 of the shoulder straps 20 and 22. A plan view of a connecting plate 28 is shown in FIGURE 5 which is provided with pairs of parallel slots 34 and 36 on the two right angular edges. An aperture 39 is provided for a purpose to be later explained. As indicated in FIGURE 1, the ends 30 and 32 of the shoulder straps 20 and 22 are adapted to be

positioned through these slots 34 and 36 to enable adjustment of the straps.

Below these connecting plates 28, and adapted to encircle the waist of a player, is a doubled plastic belt background 38. The ends 40 and 42 in front are folded back and the folds are spaced from each other as shown in FIGURES 1 and 4. This doubled plastic belt background material is of oposed colors as are the numerals "77" on the front and back of the doubled number identification 12 and 14. Slits 44 have been made in the approximately horizontal belt background 38 forming loops 47 to permit the plastic belt 46 to be inserted or woven in and out of the loops 47. It is to be noticed that straps 20 and 22 are extensions of the doubled belt background 38. A buckle 48 is positioned centrally of the front and has cooperative engagement with the folded portions 49 of the plastic belt at this location.

The end 50 of the belt 46 may be sealed, riveted or otherwise attached to the adjacent surface of the belt.

Tie-down or cords 52 are used to secure the connecting plates 28, through which the shoulder straps 20 and 22 extend, to the belt 46 or the player's trouser loops to maintain the component parts of the apparel in relative adjusted positions.

In FIGURE 2, a partial rear view of the combined sport designation has been shown with the upper portion, comparable to number identification on the front, not shown in this view. With the exception of the connecting plates 28, the upper portion in the rear is identical to that disclosed in the front.

However, in the lower portion in the rear there is provided a team identification background 54 shown attached or mounted on the belt 46. This belt, in the rear, passes through, or is woven through the loops 56 of the belt background material 38. The emblem or team designation 58 is secured by rivets, staples, or other means 60 to the facing or background 54 and may readily be separated therefrom. It is to be noticed that the stays 62, comparable to the stays 26 on the front of the apparel, are provided to accommodate or adjust the possible looseness of the straps 20 and 22 in the rear. The straps 20 and 22 pass around the torso of the wearer and both ends of each strap are attached in front to same or common connecting plate 28 as shown in FIGURE 1 to form a closed loop.

It is to be observed that certain material has been doubled to give added strength, such as disclosed in the identification backgrounds 12 and 14, as well as the belt facing 38.

In operation or use of the sport apparel, a team chooses a color background and it is turned to face the outside. The excess of the slitted belt background is then turned into match the nearest corresponding slit. The center of the slitted background is then positioned and the emblem or team identification in the rear is placed straddling the three center slits. The belt is then located or applied, weaving it through the slits, flaps and/or loops.

The top circle or number background that match the color of the belt background is then turned to face outside by turning the complete attire inside out. The attire or apparel is then put upon the player and the slitted adjustment portions are arranged so that they hang just above the belt on each side, the excess ends running just under or up to the sliding holders or flaps above. The tie-downs or string ties 52 are then secured to either the belt or to the player's trouser loops.

It is to be observed that the emblem or team designation is held securely stretched by its positioning between the slits in the belt background.

It is to be further understood that the numeral designation may be readily reversed to indicate different color, as in the case of the double belt and team designation. Further, the numerals may be changed readily as well as the teams designation.

In the practical use of the unit or apparatus, a team chooses a given color background and turns it to face the

outside. The excess slitted belt grounding is now turned in and matched to the nearest corresponding slit. The center of the slitted background is located and the emblem is positioned, straddling the three center slits. The belt is then woven through the slits and the belt unit is positioned upon the player with the excess end secured in the loop slits.

The tie-down or string ties are now secured to either the belt or the player's trouser loops. It is to be observed that the emblem display is held securely stretched by its fit between the slits in the belt background.

In the modification shown in FIGURES 6 through 9, a sliding retainer 70 for the belt 46 has been disclosed. This plastic retainer of general rectangular formation comprises side members 72 and a base 74. Cut-outs 76 are provided on each side member 72 establishing a width comparable to that of the belt 46 for the sport identification apparel that has been shown in the previous views.

Spaced grooves 78 and 80 have been formed in the base 74 and vertical serrations 82 are provided on the opposed longitudinal surfaces of the grooves. As shown in FIGURES 8 and 9, the end 84 of the belt 46 has been inserted through the grooves 78 and 80 and held fast through the grooves 78 and 80 due to the serrations 82 with the side edges of the belt abutting or fitting within the cut-outs 76.

The slide 70 is attachable to the main belting 46 by merely crimping the side edges of the belt down and pressing upon the center of the belting, thus setting the beads upon the outer edges into their slides as particularly shown in FIGURE 9. This arrangement allows movement of the retainer along the belting by sliding into the desired position or location, thus eliminating the usual necessity of threading the entire ending therethrough.

While some of the features of the subject invention have been described in detail, it is apparent that modifications and variations may be resorted to without departing from the spirit of the invention; and that accordingly, the appended claims are to afford a range of equivalent and scope fairly in keeping with our contribution to the art.

We claim:

1. In an adjustable and reversible identification apparel of plastic material for athletic contests, crossed shoulder straps, each strap having front and back portions adapted to extend around a torso of a wearer, in front and in back, numeral designation on a background of doubled plastic material on said front and back portions, said shoulder straps positioned between said doubled material; stays located on the lower portions of said straps whereby loosening of the straps is minimized, connecting plates secured to the ends of the crossed shoulder straps, each shoulder strap forming a loop adapted to extend around the torso with the respective ends of said strap attached to a respective common connecting plate, and an adjustable, reversible belt background of doubled plastic material having loops formed thereon to receive a belt of comparable material, said belt cooperating with said loops when said belt background is folded on itself and opposing belt loops aligned, a buckle secured on the ends of said belt, tie-down cords secured to each of said connecting plates and said belt whereby said connected parts are maintained in relative adjustment.

2. An adjustable and reversible identification apparel of plastic material for athletic contests, comprising a pair of crossed shoulder straps, each strap having front and back portions adapted to extend around the torso of a wearer; at least one colored identification background of doubled material of different identifying colors on opposite sides thereof, said shoulder straps passing between said sides of said identification background; connecting plates secured to the ends of said crossed shoulder straps, each shoulder strap forming a loop adapted to extend around the torso with the respective ends of said strap attached to a respective common connecting plate; a foldable, reversible, belt background of different identifying colors on opposite sides, said identifying colors corresponding to those of said identification background;

spaced slits in said belt background forming spaced belt loops thereon, said belt background being adjustable by folding back the ends of said belt background and aligning two of said belt loops formed thereon; a belt extending through said belt loops in said belt background; and means for securing said connecting plates to said belt.
